(57) CLAIM

The ornamental design for a baking crock, as shown.

DESCRIPTION

FIG. 1 is a perspective view of the inventive design for a baking crock;

FIG. 2 is an elevational view of a side of the FIG. 1 design;

FIG. 3 is a top plan view of the FIG. 1 design;

FIG. 4 is a bottom plan view of the FIG. 1 design;

FIG. 5 is a cross-sectional view taken along line 5—5 on FIG. 3;

FIG. 6 is a fragmentary perspective view of the bottom of the FIG. 1 design;

FIG. 7 is a top plan view of a second embodiment of the baking crock;

FIG. 8 is a bottom plan view of the FIG. 7 design;

FIG. 9 is a cross-sectional view taken along line 9—9 in FIG. 7;

FIG. 10 is a fragmentary perspective view of the bottom of the FIG. 7 design; and,

FIG. 11 is an elevational view of the side of the FIG. 7 design, identical to that of FIG. 2.
